ILLUMINATED STOVE

Gene H. Cripe, North Hollywood, and Richard J. Petersen, Downey, Calif., assignors to Utility Appliance Corporation, Los Angeles, Calif., a corporation of California

Application June 30, 1952, Serial No. 296,472

7 Claims. (Cl. 240—2)

The present invention relates in general to backrails for cooking stoves and, more particularly, to a backrail which carries a light source for illuminating the cooking surface of a stove and which carries a shelf movable between a lowered, retracted position and a raised, extended position, a primary object of the invention being to provide a construction wherein the cooking surface is illuminated by the light source regardless of whether the shelf is in its retracted position, or in its extended position.

In prior cooking stoves having backrails provided with light sources and movable shelves, the light sources are frequently mounted on top of the backrails so that, when the shelves are in their extended positions, they intercept the light from the light sources and prevent the light from reaching the cooking surfaces of the stoves. In other prior stoves, the light sources are mounted in the backrail below the shelves so that the latter intercept the light when retracted. The present invention avoids such interception of the light, which is an important feature.

More particularly, an object of the invention is to provide a backrail which includes, at its top, a forwardly projecting overhang, the overhang carrying a light source which directs light forwardly and downwardly toward the cooking surface along a predetermined path, and the overhang carrying a shelf which is movable between a retracted position wherein it is disposed rearwardly and below the light path and an extended position wherein it is disposed forwardly and above the light path. Thus, the light source directs light toward the cooking surface along a path which lies between the extended and retracted positions of the shelf so that the light is not intercepted by the shelf when in either its extended position, or its retracted position.

Another object is to provide a backrail which is provided, at its bottom, with a recess in which the shelf is disposed when in its retracted position, the light source being carried by the backrail above the recess so that it directs light toward the cooking surface along a path disposed forwardly of and above the retracted position of the shelf.

Another object is to provide a backrail construction wherein the shelf is pivotable between its extended and retracted positions through a predetermined arc, the light source being located in close proximity to the pivot axis of the shelf and being directed toward a point on the arc of movement of the shelf which is intermediate the ends of the arc so that the light is not intercepted by the shelf when it is in either its extended position, or its retracted position.

Another object is to provide the backrail with latch means for latching the shelf in its extended position, the latch means being engageable with a portion of the shelf.

The foregoing objects and advantages of the present invention, together with various other objects and advantages thereof which will become apparent, may be attained with the exemplary embodiment of the invention which is illustrated in the accompanying drawing and

2

which is described in detail hereinafter. Referring to the drawing:

Fig. 1 is a front elevation, on a reduced scale, of a cooking stove backrail construction which embodies the invention;

Fig. 2 is a sectional view of the backrail construction which is taken along the arrowed line 2—2 of Fig. 1, a shelf incorporated in the backrail construction being shown in its extended position; and

Fig. 3 is a view similar to Fig. 2, but showing the shelf in its retracted position.

Referring to the drawing, illustrated therein is a cook stove 10 having a horizontal cooking surface 11 which includes the usual burners or heating elements, and which may include a griddle, work space, or the like. Mounted on the stove 10 along the rear edge of the cooking surface 11 is a backrail 12 having the form of a housing the interior of which is open and contains various parts to be described. The backrail 12 is preferably formed of sheet metal as is conventional, although other materials may be used.

The backrail 12 is provided, adjacent its top, with a forwardly projecting overhang 13 which, in turn, provides a recess 14 therebelow and adjacent the bottom 25 of the backrail, the overhang 13 and recess 14 extending substantially the entire width of the stove. The overhang 13 is provided with a rearwardly and downwardly sloping lower wall 17 which also forms the top wall of the recess 14. Housed within the overhang 13 of the backrail 12 is a light source which is indicated generally by the numeral 18, the light source being shown as including two electric lamps 19 disposed in a reflector 20 which directs light from the lamps 19 downwardly and forwardly onto the cooking surface 11 through an elongated window 21 in the lower wall 17. The path taken by the light in its forward and downward travel toward the cooking surface 11 is indicated by the broken lines 22, it being noted that the light path diverges so that substantially the entire cooking surface 11 is illuminated by the light source 18. The window 21 may merely be an opening in the lower wall 17 of the overhang 13, or it may comprise a transparent material, such as glass, or a suitable plastic.

Pivotal mounted on the overhang 13 of the backrail 12 is a shelf 25 which is movable between a retracted position, shown in Fig. 3, and an extended position shown in Fig. 2. The shelf 25 includes a work surface 26 on which articles may be placed when the shelf is extended, the work surface preferably being formed of sheet metal, although other materials may be used also. The work surface 26 is connected at its ends to arms 27 which support it and which are connected to the backrail 12 by pivot pins 28, the pivot pins 28 being aligned horizontally to provide a horizontal pivot axis for the shelf 25. The arms 27 are provided with lugs 29 thereon which are engageable with lugs 30 on latch elements 31 of a latch means 32 to hold the shelf 25 in its extended position, the latch means 32 being completely disclosed and claimed in our copending application Serial No. 296,473, filed June 30, 1952, now Patent No. 2,692,749, reference to which is hereby made. Suffice it to say here that the latch elements 31 are pivotable into and out of positions wherein the lugs 30 thereon engage the lugs 29 on the arms 27, whereby the shelf 25 may be unlatched when it is desired to move it into its retracted position.

It will be noted that the pivot axis provided by the pivot pins 28 is in close proximity to the light source 18 so that, as the shelf 25 is pivoted between its extended and retracted positions, it crosses the path of the light from the light source 18 to the cooking surface 11 and is clear of the light path when in either of these positions, the shelf being retracted into the recess 14 when in

its retracted position. In other words, when the shelf 25 is in its extended position, it is disposed forwardly of the overhang 13 and thus is disposed forwardly and above the path of the light from the light source 18 to the cooking surface 11. Similarly, when the shelf 25 is in its retracted position, it is disposed in the recess 14 and is located below and behind the path of light from the light source 18 to the cooking surface 11. Consequently, the shelf 25 does not intercept any of the light directed toward the cooking surface 11 when it is in either its extended position, or its retracted position, so that the cooking surface is adequately illuminated at all times, which is an important feature of the invention.

Another way of expressing the structural relation between the shelf 25 and the light source 18 is that the light source is located approximately at the pivot axis of the shelf and between the retracted and extended positions of the shelf so that the light flows freely from the source 18 to the cooking surface 11 whenever the shelf is retracted, or extended. The distance between the extended and retracted positions of the shelf 25 is indicated by the arc 35 in Figs. 2 and 3 of the drawings, this arc representing both the angular movement of the shelf and the clearance between the extended and retracted positions thereof. As will be noted, the path of the light flowing from the light source 18 to the cooking surface 11 intercepts the arc 35 at a point, or, more accurately, in a zone, intermediate the ends of the arc so that the light path is unobstructed by the shelf when in either its extended position or its retracted position.

Thus, the present invention provides a back-rail construction which provides the advantages of both a light source for illuminating the cooking surface and a retractable shelf for the housewife's convenience, without rendering the light source ineffective for either position of the shelf. While we have disclosed an exemplary embodiment of our invention herein for purposes of illustration, it will be understood that various changes, modifications and substitutions may be incorporated in the embodiment disclosed without departing from the spirit of the invention as defined in the claims allowed to us and appearing hereinafter.

We claim as our invention:

1. In combination: a stove body having a cooking surface and having a backrail along the rear edge of said cooking surface which includes, at its top, a forwardly projecting overhang; a light source carried by said overhang and aimed downwardly and forwardly toward said cooking surface so as to direct light downwardly and forwardly toward said cooking surface along a light path; a shelf; and means for mounting said shelf on said backrail for movement relative thereto downwardly and rearwardly from an extended position wherein it is located forwardly of and above said light path to a retracted position wherein it is located rearwardly of and below said light path, whereby said cooking surface receives light from said light source for either of said positions of said shelf.

2. In combination: a stove body having a cooking surface and having a backrail along the rear edge of said cooking surface which includes, at its top, a forwardly projecting overhang; a light source housed in said overhang and aimed downwardly and forwardly toward said cooking surface so as to direct light downwardly and forwardly toward said cooking surface along a light path; and a shelf pivotally mounted on said overhang for pivotal movement about a horizontal axis which is located adjacent said light source, said shelf being pivotable relative to said overhang between an extended position wherein it is located above and forwardly of said light path and forwardly of said overhang and a retracted position wherein it is located below and rearwardly of said light path and below said overhang, whereby said cooking surface receives light from said light source for either of said positions of said shelf.

3. A combination as defined in claim 2 including latch means carried by said backrail and engageable with said shelf for latching said shelf in said extended position.

4. In combination: a stove body having a cooking surface and having along the rear edge of said cooking surface a backrail which is provided, at its bottom, with a forwardly facing recess; a light source carried by said backrail above said recess and aimed downwardly and forwardly toward said cooking surface so as to direct light downwardly and forwardly toward said cooking surface along a light path; and a shelf mounted on said backrail and movable relative thereto downwardly and rearwardly from an extended position wherein it is located forwardly of and above said light path to a retracted position wherein it is disposed in said recess and is located rearwardly of and below said light path, whereby said cooking surface receives light from said light source for either of said positions of said shelf.

5. In combination: a stove body having a cooking surface and having along the rear edge of said cooking surface a backrail which is provided, at its bottom, with a forwardly facing recess; a light source housed in said backrail above said recess and aimed downwardly and forwardly toward said cooking surface so as to direct light downwardly and forwardly toward said cooking surface along a light path; and a shelf pivotally mounted on said backrail and pivotable relative thereto between an extended position wherein it is located above and forwardly of said light path and a retracted position wherein it is located below and rearwardly of said light path and within said recess, whereby said cooking surface receives light from said light source when said shelf is in either said retracted position or said extended position.

6. The combination defined in claim 5 including latch means carried by said backrail and engageable with said shelf for latching said shelf in said extended position.

7. In a stove, the combination of: a stove body having a horizontal cooking surface and having an upright backrail along the rear edge of said cooking surface; light source means carried by said backrail adjacent the top thereof for directing forwardly and downwardly toward said cooking surface a wide light beam which intersects substantially the entire area of said cooking surface to illuminate same; a shelf; and means pivotally mounting said shelf on said backrail for movement about a horizontal pivot axis in close proximity to said light source means, said shelf being spaced from said pivot axis so that it is movable across said light beam, along a path forwardly of and below said light source means, between a lowered, retracted, generally vertical position wherein said shelf is located rearwardly of and below said light beam, and a raised, extended, generally horizontal position wherein it is located forwardly of and above said light beam, whereby substantially said entire area of said cooking surface receives illumination from said light source means irrespective of whether said shelf is in said extended position, or in said retracted position.
